UNITED STATES PATENT OFFICE.

CYRUS M. WALKER, OF KANSAS CITY, MISSOURI.

GARMENT.

1,159,439.

Specification of Letters Patent.

Patented Nov. 9, 1915.

Application filed January 21, 1915. Serial No. 3,493.

To all whom it may concern:

Be it known that I, CYRUS M. WALKER, a citizen of the United States, residing at Kansas City, in the county of Jackson and 5 State of Missouri, have invented certain new and useful Improvements in Garments; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to improvements in garments and has for its principal object to provide an improved construction whereby the drawers may be held up about the waist and at the same time prevent the shirt 20 from working up over the waist band of the drawers, whether worn inside or outside of the same. In accomplishing this object I have provided the details of structure 25 hereinafter described and illustrated in the accompanying drawings, wherein:—

Figure I is a view of a garment equipped with my improvement. Fig. II is an enlarged view of a portion of the garment, with the tab shown in Fig. I secured there- 30 to. Fig. III is an enlarged view, showing the method of folding the tab to attach the shirt to the drawers when the shirt is worn inside of the drawers. Fig. IV is a sectional view through the members when the shirt 35 is worn on the outside of the drawers. Fig. V is a similar view showing the connection when the shirt is worn inside of the drawers.

Referring more in detail to the drawings: 1 designates a garment, such as underdrawers, of ordinary construction. Secured in 40 the upper portion of the drawers at the band position is an upwardly extending tab 2 provided on its outer face with a button 5. The portion of the garment carrying the tab 45 is also provided with a buttonhole 6 adapted for receiving the button 5 when the tab is folded over, as shown in Fig. III.

To use the improvement, the shirt is provided with buttonholes 7, which are pref- 50 erably arranged at different elevations to provide adjustment in the manner herein- after set forth, and located so that when the shirt is worn outside of the drawers the but- 55 ton 5 that is carried on the tab 2 will take thereinto to prevent the shirt from work-

ing upward. Presuming the shirt to be worn beneath the drawers, the tab is folded downward, so that the button 5 may be projected through the buttonhole 6 and register within one of the shirt buttonholes 7; the 60 plurality of buttonholes in the shirt making it possible to attach the tab to fit different trunk lengths. It will be seen that by so constructing the garment, the shirt may be effectively held from working upward about 65 the waist and the drawers held at the de- sired elevation.

Having thus described my invention, what I claim as new therein, and desire to secure by Letters-Patent, is:—

1. The combination with upper and lower garments, each having a buttonhole, of a tab attached to and foldable over one of the garments, and a button on said tab projectable through the buttonholes in both gar- 75 ments when the tab is folded over its carrying garment.

2. The combination of an upper garment having a buttonhole therein, a lower garment having a buttonhole therein, a tab 80 secured to the lower garment and extending thereabove and over the last named button- hole, and a button on said tab projectable through the buttonhole in the upper gar- 85 ment when the tab is extended, and through the buttonholes in both garments when the tab is folded over the lower garment.

3. The combination with a lower garment having a buttonhole, of an upper garment having a bottom part adapted to lie within 90 or without the lower garment and having a plurality of buttonholes, each of which is adapted for registration with the button- hole in the lower garment, a tab extending from the edge of the lower garment above 95 the buttonhole therein and foldable onto said lower garment, and a button on said tab projectable through any one of the but- tonholes in the upper garment when the tab is extended or through one of the button- 100 holes in the upper garment and through the buttonhole in the lower garment when the tab is folded and the buttonholes are in registration.

In testimony whereof I affix my signature 105 in presence of two witnesses.

CYRUS M. WALKER.
